United States Patent

Des. 241,570
Patented Sept. 21, 1976

241,570

DECORATIVE LAMP

John H. Holtvoigt, Tipp City, Ohio, assignor to The Dolly Toy Company, Tipp City, Ohio

Continuation-in-part of abandoned design application Ser.
No. 173,740, Aug. 20, 1971. This application Feb. 8,
1973, Ser. No. 330,591

Term of patent 14 years

Int. Cl. D26—05
U.S. Cl. D48—20 C

FIG-4

FIG. 1 is a perspective view of a decorative lamp showing my new design;

FIG. 2 is a top perspective view thereof;

FIG. 3 is a perspective view of a second embodiment of my new design; and

FIG. 4 is a bottom perspective view thereof.

This is a continuation-in-part of design application Ser. No. 173,740, filed Aug. 20, 1971, and now abandoned.

I claim:

The ornamental design for a decorative lamp, substantially as shown and described.
